UNITED STATES PATENT OFFICE.

FRANK E. BOCORSELSKI, OF RICHMOND, VIRGINIA.

FUEL-FEEDER.

1,131,989.

Specification of Letters Patent. Patented Mar. 16, 1915.

Application filed March 14, 1914. Serial No. 824,760.

To all whom it may concern:

Be it known that I, FRANK E. BOCORSELSKI, a citizen of the United States, and residing at Richmond, in the county of Henrico and State of Virginia, have invented certain new and useful Improvements in Fuel-Feeders, of which the following is a specification.

This invention relates to fuel feeders especially adapted for feeding pulverized fuel.

The primary object of the invention is to provide an improved method and means for thoroughly agitating and mixing pulverized fuel with the aid of an air blast, before the fuel is discharged by the blast to the point of consumption.

In the use of pulverized fuel by the aid of an air blast, it is important that the fuel be supplied to its point of consumption in a finely-disintegrated state, preferably in a stream or cloud of dust, that will readily yield to the action of the blast to insure a free delivery of the fuel in the best form for thorough combustion.

The invention consists of the method of feeding pulverized fuel consisting in subjecting the same to the action of an air blast within a suitable receptacle to thoroughly agitate and disintegrate the fuel, and subsequently discharging the fuel by the same air blast.

The invention also includes the method of feeding pulverized fuel consisting in subjecting the fuel to a thorough agitation within a revolving receptacle under the combined action of centrifugal force, and an air blast, and then discharging the fuel by the same air blast.

The invention also consists of a fuel feeder comprising a receptacle provided with deflectors so constructed and so disposed within the receptacle as to cause the fuel, under the force of an air blast, to be thoroughly agitated and mixed by a whirling movement of the air, before being discharged from the receptacle by the same blast.

Another feature of the invention is to provide a revoluble receptacle provided with internal deflectors and an air tube, so that the fuel may be agitated both by centrifugal force and by an air blast simultaneously.

The invention also includes improved means for feeding the pulverized fuel to the

receptacle; improved means for directing its course of movement within the receptacle, and finally discharging the fuel from the receptacle by an air blast.

The drawing illustrates one embodiment of my invention, the construction of which will be fully described hereinafter in connection with the drawing which forms a part of this specification, and the novel features of the invention will be set forth and defined in the appended claims.

In the drawing: Figure 1 is a vertical central longitudinal section of a fuel feeder embodying the invention, in which the mixing receptacle is stationary. Fig. 2 is a transverse section of the same, on the line 2-2 of Fig. 1. Fig. 3 is a similar section taken on the line 3-3 of Fig. 1. Fig. 4 is a vertical central longitudinal section of a modified embodiment of the invention in which a revoluble mixing and agitating receptacle is employed, and, Fig. 5 is a vertical transverse section of the revoluble receptacle on the line 5-5 of Fig. 4.

Referring to Figs. 1, 2, and 3, the numeral 1 designates a spherical receptacle made up of two sections 2 and 3, each having an annular flange 4, said flanges abutting, and being secured together by bolts 5. This receptacle 1 is provided with a suitable support 6 upon which it is secured in any preferred manner.

The reference numeral 7 designates an air tube screw-threaded at one end for attachment within a threaded opening 8 at one side of the receptacle, and having its opposite end 9 flared as shown, and co-acting with a conical deflector 10 to provide a diverging passage 11. The deflector 10 projects from, and is shown as integral with, a concavo-convex plate 13, which is supported within the section 3 of the receptacle by spaced lugs or webs 14 secured to the inner face of the section 3. The plate 13 is provided on its outer side with a conical deflector 15, horizontally aligned with the inner conical deflector 10 but of materially less dimensions than the latter. Surrounding the outer threaded end of the tube 7 is a hollow conical deflector 16 having an annular inclined flange 16a secured to the inner surface of the section 2. Projecting from the outer side of the receptacle section 2 is a boss 17 formed with the threaded opening 8, and also with a horizontal socket 18, the latter serving as a bearing for one end of

a conveyer shaft 19, the opposite end of said shaft being supported in a bearing 20 projecting from the inner side of the front wall 21 of a hopper 22. The hopper is provided 5 with a tubular extension 25 within which revolves a portion of the conveyer shaft 19 and its feed screw 26. The outer end of the conveyer shaft 19 extends through a bracket bearing 27 secured to the hopper, and a belt 10 pulley 28 is mounted upon the outer end of the shaft 19 whereby the feed conveyer may be revolved from any suitable source of power.

The extension 25 of the hopper communicates through an opening 29 with a feed chamber 30 communicating at its inner side, as at 31, with the air tube 7, and at its outer side with an air pipe 31' alined with and constituting a continuation of said tube.

20 The feed chamber 30 is preferably of approximately oval form in cross-section as shown in Fig. 2, and is provided with a vertically-disposed flange 32 fitting upon a complementary flange 33 on the boss 17 to 25 which it is secured. Within the feed chamber 30 are disposed a plurality of oppositely-inclined baffle-plates 34 disposed above the lower end 35 of said feed chamber, as best shown in Fig. 2 to obstruct and retard the 30 feed of the pulverized fuel as it falls through the feed chamber to the lower portion 35 thereof, said portion 35 being interposed between the contiguous ends of the blast pipe 31, and the air tube 7 and constituting a part of the path of travel of the 35 blast.

The operation of the feeder may be explained as follows: Pulverized fuel from the hopper 22 falls upon the conveyer screw 26 40 and is fed to the mouth of the feed chamber 30 through which it falls over the baffle plates until it reaches the bottom portion 35 of the feed chamber, where the air blast entering through the pipe 31 carries the 45 fuel through the tube 7. As the fuel is discharged by the air pressure through the flared end 9 of the tube, it encounters the conical deflector 10 and is deflected through the diverged passage 11 against the concave 50 face of the plate 13 which directs it down and whirls it around within the receptacle 1, to thoroughly agitate and disintegrate the fuel, and finally force it in a thin stream within the space between the convex face 55 of the plate 13 and the inner face of the section 3 of the receptacle as indicated by arrows in Fig. 3, and finally discharges it through a central opening 36 in the section 3 opposite the deflector 15, and communicating with a discharge pipe 37 secured to the section 3, which directs the fuel to the point of consumption. The function of the hollow conical deflector 16 is to deflect the 60 whirling fuel toward the plate 13 and cooperate with the deflector 9 in directing the 65

pulverized fuel, after it is thoroughly agitated and mixed with the air under pressure, out of the receptacle.

It will be understood that the strong pressure of the air blast alone affects the whirling movement of the fuel, in the form of feeder shown in Figs. 1, 2, and 3.

To supplement the force of the air blast, by imparting a rotary motion to the mixing receptacle, is the object of the modified construction illustrated in Figs. 4 and 5 of the drawings, and reference will now be made to said figures. The revoluble receptacle comprises two semi-spherical sections 38 and 39 supported to revolve between the 75 arms 40 and 41 of a U-shaped yoke 42, having a stand or base 43. The arms are provided with alined bearings 44 and 45 to receive tubular trunnions 46 and 47 projecting centrally from the outer sides of the sections 80 38 and 39 of the mixing receptacle, respectively. Upon the trunnions 46 of the section 38 is mounted a spur gear wheel 48 meshing with a gear pinion 49 mounted upon one end of a drive-shaft 50 supported at one end in a bearing 51 of the yoke 42, and adjacent to its opposite end in a suitable bearing 52 at a distance from the receptacle. The shaft 50 may be driven either by a suitable motor (not shown) or by 85 means of a belt pulley 53 mounted on the shaft, the latter being shown broken away in Fig. 4, to illustrate that either mode of driving referred to may be selected. The revoluble receptacle is provided with an air tube 7^a, deflectors 10^a, 15^a, and 16^b, a concavo-convex plate 13^a corresponding to and in all essentials the same as the same elements shown in Fig. 1. The hopper 22^a, air blast pipe 31^a, feed chamber 30^a, and their 90 associated elements are likewise similar to those already described in connection with Figs. 1, 2, and 3, and need no further description. The operation of this modified form will be readily understood, it being 95 only stated that the revolution of the shaft 50 revolves the spherical mixer through the gears 48 and 49 and the revolution of the receptacle supplements the air blast in effecting the required mixing and agitation, the fuel being subjected to the centrifugal force of the revolution of the receptacle, as well 100 as to the action of the air blast.

The whirling course of the pulverized fuel is indicated by arrows in Figs. 4 and 5, 105 and it is obvious that the fuel will be subjected to a thorough agitation and disintegration in its travel through the feeder and finally discharged in a thin stream or cloud 110 so necessary to insure complete combustion.

While the forms of the invention herein 115 shown and described are what are believed to be preferable embodiments thereof, it is nevertheless to be understood that various 120 forms and modifications may be had with-

out departing from the spirit and scope of the invention as claimed.

What I claim as new and desire to secure by Letters Patent of the United States is:—

- 5 1. A feeder for pulverized fuel, comprising a receptacle, an air tube diametrically disposed therein, an air blast pipe communicating with one end of said tube, means within the receptacle for obstructing the fuel, and means for revolving said receptacle to disintegrate the fuel by centrifugal motion while it is being carried by the air blast for discharge by said blast centrally of said receptacle.
- 10 2. A fuel feeder comprising a circular receptacle, provided with internal oppositely disposed confronting deflectors, an air tube extending through the receptacle and flared at its discharge end, and means for feeding pulverized fuel to said receptacle.
- 15 3. A feeder for pulverized fuel, comprising a receptacle provided interiorly with diametrically - opposite deflectors, an air-tube disposed within said receptacle in alignment with said deflectors, an air blast pipe communicating with one end of said tube, and means for supplying fuel to a point between the air blast pipe and the air tube.
- 20 4. A fuel feeder comprising a mixing receptacle, means for directing an air blast therein, and means within the receptacle to cause pulverized fuel to be agitated and follow a circuitous path in its travel toward the discharge opening of the receptacle, said means consisting of a concavo-convex plate

and a deflector opposite the discharge end of said air blast means.

5. A fuel feeder comprising a mixing receptacle, an air tube disposed diametrically within the receptacle, and adapted to receive an air blast, and means within the receptacle for agitating and mixing the fuel under the action of the blast, comprising a concavo-convex plate, at one side of the receptacle and oppositely disposed deflectors at diametrically opposite sides of the receptacle.

40 6. A fuel feeder comprising a mixing receptacle, an air tube disposed diametrically within the receptacle, and adapted to receive an air blast, and means within the receptacle for agitating and mixing the fuel under the action of the blast, comprising a concavo-convex plate provided with oppositely projecting conical deflectors.

45 7. A fuel feeder comprising a receptacle provided with confronting deflectors arranged within the receptacle, an air tube extending through the receptacle, an air blast pipe aligned with said tube, means within the receptacle for directing the fuel in opposite directions around the inner surface of the receptacle in its course toward the discharge opening of the receptacle.

50 In testimony whereof I affix my signature in presence of two witnesses.
